UNITED STATES PATENT OFFICE.

ROBERT GARRET, OF FREEDOM, PENNSYLVANIA.

BRICK-KILN.

SPECIFICATION forming part of Letters Patent No. 498,642, dated May 30, 1893.

Application filed August 30, 1892. Serial No. 444,586. (No mode.)

To all whom it may concern:

Be it known that I, ROBERT GARRET, residing at Freedom, in the county of Beaver and State of Pennsylvania, have invented certain new and useful Improvements in Brick-Kilns, of which the following is a specification.

My invention relates to brick kilns in which a combined up and down draft is employed, and it has for its object to provide a kiln of this character simple in its construction, in which the heat products are thoroughly disseminated among the ware in such manner as to quickly and evenly burn it at all parts of the kiln.

With other objects in view, all of which will hereinafter be fully set forth, my invention consists in the peculiar combination and novel arrangement of parts, all of which will hereinafter be fully described in the specification and particularly pointed out in the claims, reference being had to the accompanying drawings, in which—

Figure 1 is a horizontal section of my improved brick kiln on the lines 1—1 2—2 3—3 and 4—4 Fig. 2. Fig. 2 is a longitudinal section thereof on the line 2 2 Fig. 1 and Figs. 3 and 4 are detail views hereinafter more particularly referred to.

Referring to the accompanying drawings A indicates the kiln body which is preferably circular in shape as shown, although in some instances it may be desirable to make it square or other shape; and B indicates the floor, which is practically a solid one it being formed of bricks laid alternately on their flat sides and on edge, with an inch of dirt between them to make the floor air tight.

Beneath the floor are arranged four independent flue sections C, each of which is formed with a series of bridge walls c, spaced apart, whereby a series of heat chambers c', are formed to thoroughly spread the heat under the floor. Each flue section C is connected with a furnace D, and such sections communicate with a series of short vertical flues E, which open up through the floor B and discharge into the interior of the kiln.

Below the floor flues C are arranged the main draft flues F which extend under the kiln floor at right angles to each other, and are connected at their outer ends with the

stacks G. These flues F communicate with the kiln chamber through a series of down draft openings H which extend from such flues up through the kiln floor. Each of the 55 draft flues F is horizontally divided as at F' whereby lower damp air chambers F² are formed, with which the floor flues communicate, through the flue sections I, such chamber being formed by setting the bricks alternately endwise and flat with dirt between them to render the division wall practically air tight. By this construction I am enabled to draw off the damp air from the kiln chamber during the operation of filling and during 65 the time the green ware is in the kiln. This I consider of great advantage, as in the kilns usually employed, much of the lower ware is pressed out of shape by the continued circulation of damp air in the bottom of the kiln 70 chamber. By providing means for drawing off such air, the ware as it is piled up has the moisture gradually drawn out of it, leaving it as it were, in a semi dry state, before the furnaces are started. It will thus be seen 75 that the ware at the bottom will thereby retain its original shape, and being in a partially dry state will thereby burn more uniform in a less time and with a much less fuel consumption than in the ordinary way.

The construction so far described, provides for an up draft burn, to combine with it an additional up draft, or a combined up and down draft, I employ the means most clearly shown in Fig. 2 of the drawings, such means 85 consisting of four furnaces J arranged intermediate the furnaces D but at a point above the kiln floor such furnaces discharging into pockets or fire chambers K projected into the interior of the kiln chamber and open at the 90 top as shown.

With each of the furnaces communicates a flue or channelway L formed in the side walls of the kiln, (see Figs. 2 and 4) which have dampers l near their upper ends and which 95 extend down and communicate with floor flues, fed from the lower furnaces D. It will be noticed that by closing the dampers in the flues L the fire from the furnaces J will be discharged into the pockets K, pass over the 100 tops thereof, enter the ware and be drawn down to commingle with the up draft heat and

pass off with it through the down draft flues in the floor, into the stack flues. If desired the dampers *l* may be opened and a part of the heat of the furnaces *J* will be deflected 5 and carried into the floor flues.

By arranging a number of furnaces *J* each with independent fire pockets at its rear end, and a number of floor flue sections with an independent furnace *D* for each, the fire in 10 the several furnaces *D* and *J* can be so regulated as the condition of the ware at the different portions of the kiln may warrant.

The kiln chamber dome is formed with the usual cooling outlets in its top and the stacks 15 with the usual dampers.

Having thus described my invention, what I claim, and desire to secure by Letters Patent, is—

1. A brick kiln having a series of hot air 20 chambers under the floor, and having branch outlets opening into the kiln chamber, stack flues having branch flues opening through such kiln floor, furnaces discharging into the hot air chambers, openings in the kiln wall 25 above the floor, a second set of furnaces discharging into the aforesaid openings in the kiln wall, and valved flues connecting such openings and the hot air chambers under the kiln floor, all arranged substantially as shown 30 and described, whereby a combined up and down draft is obtained and whereby a portion of the heat products of the upper furnaces can be deflected to discharge into the hot air chambers under the floor to pass out 35 with the up draft, as set forth.

2. In a brick kiln having a down draft, the combination with the stack and the kiln

chamber, of stack flues having damp air compartments communicating with kiln chamber and opening into the stack substantially as 40 and for the purpose described.

3. A brick kiln having a non slatted floor section, a series of independent hot air chambers under such floor having discharge flues opening into the kiln chamber, furnaces for 45 each of such hot air chambers, the stacks, the stack flues having flue sections opening into the kiln chamber, said stack flues each formed with a damp air compartment opening into the stack and flue ways connecting 50 the hot air chambers with the damp air compartments substantially as and for the purpose described.

4. An improved brick kiln having its floor provided with discharge flues, the stack flues 55 under such floor, with which such discharge flues connect, said stack flues having damp air compartments, a series of hot air chambers under the floor having flues opening up through such floor, the furnaces *D*, discharging 60 into the said hot air chambers, a series of pockets *K* open at their top in the kiln chamber a series of furnaces *J* discharging into such pockets the valved flues *L* connecting the furnaces *J* and the hot air chambers and the flues *I* connecting such hot air chambers 65 with the damp air compartments in the stack flues all arranged substantially as shown and for the purposes described.
